CLAIM

I claim the ornamental design for a beverage container with strap, as shown and described.

DESCRIPTION

FIG. 1 is a top perspective view of a beverage container with strap showing my new design, the strap of which is shown in a retracted orientation for clarity of disclosure;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top perspective view thereof with the strap shown in an expanded orientation for clarity of disclosure; and, FIG. 9 is another top perspective view thereof.

The portions of the beverage container with strap shown in broken lines form no part of the claimed design.
